UNITED STATES PATENT OFFICE.

LEO F. ADT, OF TROY, NEW YORK.

NOSE-GUARD FOR EYEGLASSES.

No. 877,625.

Specification of Letters Patent.

Patented Jan. 28, 1908.

Application filed March 6, 1905. Serial No. 248,427.

To all whom it may concern:

Be it known that I, LEO F. ADT, of Troy, in the county of Rensselaer and State of New York, have invented certain new and useful 5 Improvements in Nose-Guards for Eye-glasses; and I do hereby declare the following to be a full, clear, and exact description of the same, reference being had to the accompanying drawings, forming a part of this 10 specification, and to the reference-numerals marked thereon.

My present invention relates to improvements in nose-guards for eyeglasses, and the object of my invention is to provide certain 15 improvements in nose guards particularly of that kind employing a main supporting pad and a supplemental pad for steadyng the eyeglasses to prevent tilting while they are supported by the main supporting pads, 20 whereby the guards may be cheaply manufactured and readily applied to the mountings and adjusted or otherwise adapted to the wearer's nose, and which in use will occupy such a position on the nose as to 25 afford ample security and firmness without unduly pinching the wearer's nose.

To these and other ends my invention consists in certain improvements and combinations and arrangements of parts to be hereinafter more fully described, the novel features being pointed out in the claims at the 30 end of this specification.

In the drawings: Figure 1 is a rear elevation of a mounting with the lenses attached 35 showing nose guards embodying my invention applied thereto; Fig. 2 is a perspective view of the mounting and guard, portions being omitted; and Fig. 3 is a transverse sectional view on the line 3—3 of Fig. 1 looking 40 toward the right, showing the positions of the main and supplemental portions usually occupy relatively to the nose.

My present improvements are shown in the present embodiment as applied to an 45 ordinary mounting comprising the bridge spring 1 attached at its ends to the lens-attaching devices 2 and 3, the latter in turn being secured to the lenses 4 and 5 respectively. These attaching devices may be of 50 any desired form and are provided at their inner ends with a substantially vertically extending seat 6 for the reception of the ends of the bridge 1 and also the attaching portions of the guards. In their present form 55 these guards are composed of a single piece of preferably flat material, an intermediate

portion 7 of which is formed to enter the seat 6 of the attaching device and is perforated to receive the fastening screw 8, and to this intermediate attaching portion the 60 arm 9 extends in a direction downwardly and rearwardly to form the main supporting portion of the nose guard which is adapted to bear flatwise against the side of the wearer's nose. Extending in an opposite direction 65 from the intermediate attaching portion of the guard and forming a continuation of the arm 9 is a shank 10 which is formed by an edgewise bend of the material of the guard, the said shank extending upwardly from the 70 intermediate attaching portion and bending rearwardly and downwardly, and to the free end of this shank is attached the auxiliary or supplemental nose-bearing portion which is formed by doubling the shank upwardly 75 and preferably providing the free end of the doubled portion with an enlarged nose-bearing portion 11, and this supplemental nose-engaging portion 11 usually occupies a position in rear of and substantially on the same 80 level as the intermediate attaching portion of the guard.

The guard described is made up of substantially a continuous strip of material an intermediate portion of which forms the attaching portion for the guard and the lower and upper extensions thereof comprise the main and supplemental nose engaging portions thereof, and it may obviously be formed of a straight strip of material by simply bending it edgewise and flatwise for the respective nose-engaging portions, or it may be punched at a single operation from sheet material, and in case the particular form of supplemental pad 11 is employed the free 95 end of the shank 10 is doubled flatwise, and in each case there are no sharp angles or corners which are liable to cause breakage. Of course a supplemental nose-engaging pad of any desired form may be employed some 100 forms of which would further simplify and cheapen the cost of making the guard, but I prefer to employ a form substantially as that shown, for the rearwardly and downwardly extending shank 10 is of sufficient length to 105 enable the supplemental pad to be adjusted bodily inwardly and outwardly *i. e.* planes parallel with that of the optical axes of the lenses without disturbing the relation of the nose engaging surface of the auxiliary pad to 110 the side of the wearer's nose, and in employing the looped or double portion for con-

necting the auxiliary pad and the shank, ample adjustment of the auxiliary pad is insured without disturbing the distance between the centers of the lenses to accommodate the mountings to noses of different sizes and widths. Moreover, by providing the doubled portion for connecting these auxiliary pads and the shanks, the distance of the supplemental pads in rear of the lenses 10 may be readily adjusted by bending the pad 11 edgewise and thereby twisting the bend in the doubled portion and a yielding pressure is produced upon the wearer's nose.

When the eyeglasses occupy a proper position on the nose of the wearer, the arm 9 of the guard which extends obliquely relatively to the plane of the lenses will occupy a position approximately at right angles to the front of the nose to sustain the weight of the 20 eyeglasses and to prevent the lateral swinging of the eyeglasses, and the auxiliary or supplemental pads will engage upon opposite sides of the nose at points above the portions 9 and offset from the line of the lower portions 9 of the guard and thereby steady the eyeglasses and prevent their tilting about the lower arms 9, and by arranging the main and supplemental portions of the guards in the manner described, ample security and rigidity is obtained without unduly pinching the 30 wearer's nose.

I claim as my invention:

1. In eyeglasses, the combination with the lenses, the bridge connecting them and the 35 attaching devices for the bridge and guards, of nose guards each embodying an intermediate attaching portion, a nose-engaging portion extending downwardly from the lower end of the attaching portion and arranged 40 obliquely rearwardly in relation to the plane of the lenses, and a shank doubled upon itself and extending rearwardly from the upper end of the attaching portion and provided with a supplemental nose-engaging 45 portion.

2. In eyeglasses, the combination with the lenses, the bridge connecting them and the attaching devices for the bridge and guards, of nose guards each embodying a vertically-extending attaching portion, a downwardly-extending arm arranged in rear and obliquely to the plane of the lenses and adapted to engage the wearer's nose, and a shank extending from the upper end of the vertically-arranged attaching portion having an upwardly opening loop and a supplemental nose-engaging portion on the shank beyond the loop and offset from the said arm.

3. In eyeglasses, the combination with the lenses, the bridge connecting them, and the attaching devices for the bridge and guards, of nose guards each embodying an intermediate vertically-extending attaching portion, a downwardly-extending arm forming a continuation of the attaching portion adapted to

engage the wearer's nose, and a rearwardly-extending shank attached to the upper portion of the attaching portion having an inwardly doubled arm thereon forming a supplemental nose pad.

4. In eyeglasses, the combination with the lenses, the bridge connecting them, and the attaching devices for the bridge and guards, of nose guards each embodying a vertically-extending attaching portion secured in the 75 attaching device and having a rearwardly and downwardly extending shank attached to its upper end, and a nose-engaging portion connected to the free end of the shank by a bend in the material substantially in a direction parallel to the plane of the lenses.

5. In eyeglasses, the combination with the lenses, the bridge connecting them, and attaching devices for the spring and guards, of nose guards each embodying a vertically-extending attaching portion secured by the attaching device, a rearwardly and downwardly-extending shank attached to the upper end of the attaching portion having its free end doubled in a direction substantially 90 parallel to the plane of the lenses to form a nose-engaging portion.

6. In eyeglasses, the combination with the lenses, the bridge connecting them and the attaching devices for the spring and guards, of nose guards each embodying an intermediate vertically-extending attaching portion secured to the attaching device, a downwardly-extending arm forming a lower extension of the attaching device and adapted 100 to engage the wearer's nose and a shank attached to the upper end of the attaching portion extending rearwardly and having its end inwardly doubled to form a yieldingly supported supplemental nose-engaging portion 105 which is offset from the downwardly-extending arm.

7. A nose guard for eyeglasses composed of a single piece of flat material embodying an intermediate attaching portion, an arm 110 forming a continuation of the attaching portion in one direction, a shank forming a continuation of the attaching portion and extending in a direction laterally of the said arm, the end of the shank being doubled inwardly and in a direction flatwise of the material to form an adjustable pad.

8. In eyeglasses, the combination with the lenses and the bridge connecting them, of a nose guard formed of sheet material having a 120 lower bearing surface and a supplemental nose-engaging surface or pad arranged above and in rear of the lower bearing surface and connected thereto by a pliable arm upwardly opening loop flatwise of the material for permitting adjustment of the upper nose-engaging surface in a direction forwardly and rearwardly of the lenses.

9. A nose guard formed of sheet metal having a lower bearing portion and a bearing pad 130

arranged above and in rear of the bearing portion and connected thereto by a **U**-shaped supporting arm extending from the pad downwardly and then doubled inwardly 5 and upwardly with the flat surfaces of the metal lying in different planes.

10. In eyeglasses, the combination with the lenses, and bridge connecting them, of a nose guard formed of sheet metal and embodying a nose-engaging portion, and a pliable connecting arm or shank having an upwardly opening loop in substantially the direction of the plane of the lenses, and having an attaching portion leading downwardly to 15 its point of attachment to the lens.

11. In eyeglasses, the combination with the lenses having suitable attaching devices, and a bridge connecting them, of nose guards formed of pliable material each embodying a 20 connecting arm extending rearwardly and downwardly from the top of the attaching device, and thence doubled inwardly and upwardly to form a nose-engaging pad or surface which may be adjusted in a direction 25 forwardly and rearwardly of the plane of the lenses without altering substantially the relative height of said pad or surface.

12. In eyeglasses, the combination with the lenses having suitable attaching devices, 30 and a bridge connecting them, of nose-guards composed of flat material each embodying a lower nose bearing surface, and an arm extending rearwardly from the top of the at-

taching device, and having an upwardly opening loop therein flatwise of the material to 35 form a yielding nose-engaging surface or pad.

13. In eyeglasses, the combination with the lenses having attaching devices thereon and a bridge connecting them, of nose guards connected to the attaching devices and having arms arranged in rear of the latter and yielding nose-engaging portions doubled inwardly and upwardly from said arms. 40

14. In eyeglasses, the combination with the lenses, and a bridge connecting them, of 45 nose guards attached to the lenses each composed of flat material and embodying an arm arranged in rear of the point of attachment and extending above the latter, the lower end of said arm being doubled inwardly, 50 thence extending upwardly to form a yielding nose-engaging portion.

15. In eyeglasses, the combination with the lenses and the bridge connecting them, of nose guards each comprising a shank extending rearwardly and downwardly, and a nose-engaging portion connected to the downwardly extending portion by an inward and upward bend in the material substantially 55 in a direction parallel to the plane of the lenses. 60
